(57) **CLAIM**

The ornamental design for a finger-lift handle for a sliding window, as shown and described.

DESCRIPTION

FIG. 1 is a perspective view of a finger-lift handle for sliding window showing our new design;

FIG. 2 is a front elevational view thereof;

FIG. 3 is a rear elevational view thereof;

FIG. 4 is a right side elevational view thereof, the left side elevational view being a mirror image thereof;

FIG. 5 is a top plan view thereof; and,

FIG. 6 is a bottom plan view thereof.

The opposing side elevation view of the finger-lift handle for a sliding window, although not depicted, is a mirror image of the view of FIG. 4.
